UNITED STATES PATENT OFFICE

ARCHIE H. BECHTOL, OF DAYTONA BEACH, FLORIDA, AND WALTER A. TRATSCH, OF CHICAGO, ILLINOIS

DESIGN FOR A GAME BOARD

Application filed June 8, 1932. Serial No. 44,021. Term of patent 14 years.

To all whom it may concern:

Be it known that we, ARCHIE H. BECHTOL and WALTER A. TRATSCH, both citizens of the United States, residing at Daytona Beach, Florida, and Chicago, Illinois, respectively, have invented a new, original, and ornamental Design for Game Board, reference being had to the accompanying drawing, forming part thereof.

Fig. 1 is a plan view of a game board, showing our new design;

Fig. 2 is a sectional view of said board taken as on the line 2—2 of Fig. 1 and looking in the direction of the arrows; and

Fig. 3 is a sectional view of said board taken as on the line 3—3 of Fig. 1 and looking in the direction of the arrows.

We claim:

The ornamental design for a game board as shown.

In testimony whereof we affix our signatures.

ARCHIE H. BECHTOL.
WALTER A. TRATSCH.
